SWITCH HANDLE CONTROL MECHANISM
FOR DISPENSING PUMPSChester T. Neal, Springfield, Mass., assignor to
Gilbert & Barker Manufacturing Company,
West Springfield, Mass., a corporation of Mas-
sachusettsApplication May 5, 1937, Serial No. 140,874
Renewed June 30, 1938

6 Claims. (Cl. 221—95)

This invention relates to an improvement in liquid dispensing apparatus such as a gasoline dispensing pump of the type comprising a register indicator for displaying the amount of the gasoline dispensed.

As is customary in such dispensing pumps, the register has a manually actuated device for resetting its indicator to zero so that the quantity of each dispensing operation may be accurately 10 and separately registered and the present improvement relates more particularly to means for inducing the pump attendant to perform the resetting operation of the register prior to the start of each new dispensing operation.

15 The particular features of the invention and advantages thereof will be more clearly apparent from the following description taken in connection with the accompanying drawings, in which

20 Fig. 1 is a front elevation of the entire pump casing with a portion of the casing removed to show interior parts;

Fig. 2 is a right side elevation of the pump casing with the relative position of some of the principal parts indicated thereon;

25 Fig. 3 is a detached side elevation of the motor switch handle for the pump and its mounting;

Fig. 4 is a fragmentary section along line 4—4 of Fig. 3;

Fig. 5 is a similar section along line 5—5 of 30 Fig. 3;

Fig. 6 is a partial end view of the switch handle bracket showing behind the same in dotted lines one position of the locking beam and its associated parts; and

35 Fig. 7 is a similar view showing the other position of said locking beam and associated parts.

Referring more particularly to the drawings, 1 indicates the pump casing, 2 the casing of a combined motor and pump unit, and having integral 40 therewith the casing 3 for containing the motor switch as is well understood. The liquid fluid or gasoline is drawn by the pump through the pipe 4 from a source of supply not shown and forced out through delivery pipe 5 and meter 6 and finally 45 through dispensing hose 7 and nozzle 8. The nozzle guard 9 is adapted to rest on a fixed support 10 extending from the pump casing and when on said support the guard 9 interferes and prevents the turning to "on" position of the motor switch handle 11. The switch handle 11 is fixed to a turnable shaft or stem 12 mounted in a bracket 13, the latter being secured to the pump casing.

As shown in Fig. 3, the inner end of said handle stem 12 has fixed thereto an arm 14 connected

by link 15 to an arm 16 for operating the motor switch within the casing 3. In Fig. 2 the motor switch handle 11 is shown in its "off" position for shutting off the pump motor and the line of the "on" position is also therein indicated. As shown in Figs. 4 and 5, the movement of the switch handle 11 between its "on" and "off" positions is limited by stop pins 17 and 18 fixed to the stem 12 coacting with stop lugs 19 and 20 fixed to the bracket 13.

10 The register indicator for the pump is shown generally at 21 and is provided with the usual number dials 22 for indicating the quantity of gasoline dispensed in terms of gallons and in terms of cost value as is the present day practice with such registers. The register is driven in the usual manner through shaft 23 from the fluid operated meter 6. The resetting mechanism, for returning the indicator dials 22 to zero after the dispensing operation, comprises a crank handle 25 fixed 15 to a reset shaft 26 which extends across the pump casing and is permanently clutched to a cam collar 27 mounted in the bracket 13. It will be understood that the resetting shaft 26 when revolved through a complete revolution (counter-clockwise as one faces the handle 25) operates the usual devices (not shown) for returning the indicator dials 22 to zero.

20 Referring more particularly to Figs. 6 and 7, the switch handle stem 12 has loosely mounted 30 for a partial and relative rotation thereon a resist member in the form of a cam collar 28. As shown in Figs. 3 and 4, the relative movement of the cam collar 28 on the stem 12 is limited by a pin 29 fixed in stem 12 and extending into a segmental 35 slot 30 formed in a reduced shoulder of said collar 28. A coil spring 31 has one end 32 thereof fixed to the handle stem 12 at a pin 17 thereof and the other end of the coil spring is fixed into the collar 28 by an anchoring projection 33 of said 40 spring. The tension of the spring 31 tends to rotate the cam collar 28 counterclockwise and to rotate the handle stem 12 clockwise relatively to one another until the pin 19 abuts the right hand 45 wall of the segmental slot 30, as viewed in Fig. 4. According to this construction, whenever the handle 11 and its stem 12 are turned to "on" position, the cam collar 28 tries to follow up said movement because of its spring connection to the stem 12. However, if the cam collar is prevented, 50 under circumstances hereafter described, from thus following up a turning of the stem 12, the spring 31 is placed under greater tension tending to pull back the handle 11 to its "off" position, due to the non-follow-up movement of the cam collar 55

or resist member 28. On the other hand, if no means interpose to prevent the follow-up action of collar 28 with respect to stem 12, then the collar will turn back and forth with said stem in the 5 movements of the latter between its "off" and "on" positions.

The means for preventing the follow-up movement of the cam collar 28 so that it yieldingly resists a turning on of the switch handle 11 will 10 now be described in connection with Figs. 6 and 7. Pivotedly mounted on stud 34 projecting from the bracket 14 is a two-armed locking beam 35. One end 36 of this locking beam works against the peripheral surface of the cam collar 28 (at one 15 side of cam 50) and is adapted to drop into a cam notch 37 formed in said surface and having a stop shoulder 38 whereby when the end 36 is in said notch the collar 28 will be prevented from clockwise movement. The other end 39 of said locking beam 35 works against the peripheral surface of the cam collar 27 (at one side of cam 51) and is 20 adapted to drop into locking notch 40 for preventing rotation of said reset shaft 26. The shoulder 41 of said notch 40 is sufficiently beveled 25 to permit the reset shaft 26 being rotated clockwise, viewing Fig. 7, upon application of extra force, and camming said end 39 out of the notch 40, except when the end 36 of said beam 35 is resting upon the solid unnotched portion of said 30 collar 28. In said latter condition which is the position with the switch handle 11 in "on" position, the end 39 when in notch 40 positively locks the reset shaft from being operated. It will be understood that the reset shaft 26 in its resetting action turns clockwise when viewing Fig. 7.

The means for shifting and holding the locking beam 35 into its two different positions as shown in Figs. 6 and 7 comprises a loading spring 42 mounted on a toggle rod 43, one end of which rod 40 is pivotally connected at 44 to a toggle plate 45 and the other end of which rod slides through a rocking pivot stud 46 extended from the bracket 13. The spring 42 is interposed under compressed tension between said pivot stud 46 and a shoulder on said rod 43. The toggle plate 45 is a bifurcated member straddling the beam 35 and pivoted on the stud 44. Between the side members of said toggle plate 45 are mounted studs or rollers 47, 48 and 49. The cam collar 28 is formed with a cam 50 which is in a plane at one side of the beam 50 35 and in the plane of said roller 47 so as to act thereagainst. Similarly, the cam collar 27 on the reset shaft 26 is provided with a cam 51 adapted to act against the rollers 48 and 49 of the plate 55 45. It will be understood that when the cam collar 28 turns clockwise its cam 50 acts against roller 47 to throw the toggle 43, 45 from the position shown in Fig. 7 to the position shown in Fig. 6, and that when cam collar 27 rotates clockwise its cam 51 acting against the rollers 48 and 49, throws the toggle combination 43, 45 from the position shown in Fig. 6 to that shown in Fig. 7. With the toggle in the position shown in Fig. 6 roller 49 bears against a shoulder of said beam 35 whereby the loading spring 42 tends to 60 rock the beam 35 anticlockwise to bring its end 36 into the notch 37 of said cam collar 28, and when the toggle is in the position shown in Fig. 7 the roller 47 bears against the beam 35 whereby the loading spring 42 tends to remove the end 36 65 from the notch 37 and to press the end 39 into the notch 40 of cam collar 27.

The operation of the above described mechanism in connection with the operation of the pump will now be described. Assume that the

pump attendant has just completed a dispensing operation and has turned off the motor switch, but has not yet operated the reset mechanism. The switch handle 11 thereof will then be in the "off" position shown in Fig. 2. The toggle 43, 45 5 will be at the left as shown in Fig. 6, having been thrown to this position by the previous "on" movement of the switch handle 11. The loading spring 42 presses the roller 49 against the beam 35 and holds its end 36 in the notch 37 of said 10 cam collar 28, whereby said cam collar 28 cannot turn clockwise.

If in this condition of the parts the attendant fails to operate the reset crank 25 for returning the register to zero, but on the contrary turns on 15 the motor switch for a new dispensing operation, he does so against the resisting force of the spring 31 because since the cam collar 28 is locked against its follow-up movement with the stem 12 said stem can only be turned by further compression of the spring 31. The resistance thus offered by the spring 31 to the turning on of the switch handle 11 will warn the attendant that he has failed to operate the reset mechanism. Furthermore under these conditions the operator can 20 only keep the motor switch on and the pump in operation by manually holding the handle 11 in its "on" position. If the attendant lets go of the handle 11 it will move back to "off" position and stop the pump under the force of the spring 31. 25 However, the attendant being warned by the resistance of said spring 31 that the reset mechanism has not been operated, he should immediately operate the same by turning the reset shaft 26 a complete revolution through the handle 25. 30 The turning of the reset shaft will then carry its cam 51 against the rollers 48 and 49 and throw the toggles 43, 45 to its right hand position shown in Fig. 7. In this position the roller 47 bears on the beam 35 and the loading spring 42 will rock 40 said beam to withdraw its end 36 out of notch 37 and release the heretofore locked cam collar 28. Upon said release the cam collar 28 under force of its spring 31 immediately follows up to the "on" 45 position of the stem 12 and thereby removes all 45 resistance of said spring 31 to said "on" position of the switch handle 11. Under these conditions the attendant may let go of the switch handle 11 and it will remain in "on" position so that the dispensing can be proceeded with.

The normal and proper way for the attendant to operate the mechanism in performing a dispensing operation when the switch handle is in "off" position as shown in Fig. 2, is to first rotate the reset shaft 26 by handle 25 before turning on 55 the switch handle 11. For instance, with the parts as shown in Fig. 6 with the switch handle 11 off and the collar 28 locked, a revolution of the reset shaft 26 will move cam 51 to throw the toggle 43, 45 to the right hand position of 60 Fig. 7 and release the collar 28 while the switch handle 11 is still in its "off" position. Thereupon the switch handle 11 when subsequently turned to "on" position will meet with no resistance from the spring 31 since the collar 28 being unlocked 65 will readily follow up the movement of said switch handle stem 12.

By the arrangement above described the pump attendant may at all times whether or not the reset mechanism is operated, turn on the motor 70 switch for starting the dispensing operation, but unless the reset shaft has been revolved previously to turning on the switch handle, the dispensing cannot be continued except by manually holding said handle in its "on" position against the ten- 75

sion of the spring. On the other hand, by operating the reset mechanism before turning the switch handle on the latter is moved on without resistance and will remain in its "on" position 5 without being manually held on, and the attendant can walk away from the pump for more conveniently servicing an automobile with gasoline. It is expected that the warning given by the resist member and its spring, together with the convenience of being able to leave the pump, will be a sufficient inducement for the attendant to always operate the pump in the proper sequence of steps, viz., first reset and then turn on the motor.

I claim:

- 15 1. In liquid dispensing apparatus of the type having means for establishing flow, a register for indicating the quantity of liquid dispensed and reset mechanism for zeroizing said register, control mechanism comprising a control handle movable 20 to "on" and "off" positions corresponding to starting and stopping the flow, a spring for resisting the movement of said handle to "on" position, said spring adapted to be overcome by manual force applied to said control handle and tending 25 when stressed to return said handle to its "off" position, and means actuated by the zeroizing operation of said reset mechanism to remove the resisting action of said spring on said control handle.
- 30 2. In liquid dispensing apparatus of the type having means for establishing flow, a register for indicating the quantity of liquid dispensed and reset mechanism for zeroizing said register, control mechanism comprising a control handle movable 35 to "on" and "off" positions corresponding to starting and stopping the flow, a resist member connected by a spring to said control handle for being moved therewith and adapted when held from movement to permit independent movement of 40 said handle to its "on" position against the stress of said spring, a movable stop for said resist member, moving into active position upon the cessation of each dispensing operation, and means actuated by the zeroizing operation of said 45 reset mechanism to move said stop into inactive position with respect to said resist member.
3. In liquid dispensing apparatus of the type having means for establishing flow, a register for indicating the quantity of liquid dispensed and reset mechanism for zeroizing said register, control mechanism comprising a control handle movable to "on" and "off" positions corresponding to starting and stopping the flow, a resist member connected by a spring to said control handle for being moved therewith and adapted when held from movement to permit independent movement of said handle to its "on" position against the stress of said spring, a movable stop for said re-

sist member, means operated by the movement of said control handle to "off" position to render said stop active, and means actuated by the zeroizing operation of said reset mechanism to render said stop inactive with respect to said resist 5 member.

4. In liquid dispensing apparatus of the type having means for establishing flow, a register for indicating the quantity of liquid dispensed and reset mechanism for zeroizing said register, control 10 mechanism comprising a control handle and stem fixed thereto movable to "on" and "off" positions corresponding to starting and stopping the flow, a resist member loosely carried on said stem and connected thereto by a spring to move therewith, 15 a movable stop for said resist member moving into active position upon the cessation of each dispensing operation, and means actuated by the zeroizing operation of said reset mechanism to move said stop into inactive position with respect 20 to said resist member.

5. In liquid dispensing apparatus of the type having means for establishing flow, a register for indicating the quantity of liquid dispensed and reset mechanism for zeroizing said register, control 25 mechanism comprising a control handle and stem fixed thereto movable to "on" and "off" positions corresponding to starting and stopping the flow, a resist member loosely carried on said stem and connected thereto by a spring to move therewith, 30 a movable stop for said resist member, means operated by the movement of said control handle to "off" position to render said stop active, and means actuated by the zeroizing operation of said reset mechanism to render said stop inactive 35 with respect to said resist member.

6. In liquid dispensing apparatus of the type having means for establishing flow, a register for indicating the quantity of liquid dispensed and reset mechanism for zeroizing said register, control mechanism comprising a control handle and stem fixed thereto movable to "on" and "off" positions corresponding to starting and stopping the flow, a resist member loosely carried on said stem and connected thereto by a spring to move therewith, 40 a pivoted locking beam for said resist member, a loading spring for said pivoted beam adapted to be shifted to a locking side thereof to place said beam in active position and to an unlocking side thereof to place said beam in inactive position 45 with respect to said resist member, means operated by the movement of said control handle to "on" position to shift said loading spring to the locking side of said pivoted beam, and means actuated by the zeroizing operation of said reset 50 mechanism to shift said loading spring to the unlocking side of said pivoted beam.

CHESTER T. NEAL.
